UNITED STATES PATENT OFFICE

2,646,213

FAN

George E. Martin, Chicopee, Mass.

Application November 30, 1951, Serial No. 259,251

2 Claims. (Cl. 230—257)

1

My invention relates to new and useful improvements in a fan, and is directed more particularly to the type of fans employed for producing circulation of air in warm weather, which fans are usually driven by small electric motors.

It is the principal object of my invention to provide a novel and improved construction of the type in which not only a horizontal rotary motion is imparted to the fan but also a vertical or nearly vertical oscillation is imparted thereto and there is the further provision of a unique and novel means by which such different motions may be obtained simultaneously with each other, or, if desired, may be obtained individually and separately and independent of each other.

That is to say, according to my invention, my fan is so designed as to provide means by which the direction of air currents is changed or affected simultaneously in two different planes, as for example, oscillating the fan sidewise in a horizontal plane and at the same time moving the fan up and down in a vertical plane and further to provide means for adjusting the mechanism whereby the horizontal and/or vertical oscillation can be varied as desired.

The fan of my invention is so designed and constructed that it may oscillate not only about a horizontal or nearly horizontal axis but also about a vertical or nearly vertical axis, whereby the now present objectionable inadequacies and insufficiencies of known prior art fans are overcome in a construction wherein the area of air circulation is greatly increased.

One of the primary purposes of my invention is to provide structural and operational improvements in devices of the class to which reference has been made, which improvements provide important, distinct advantages in strength, durability and the like and offer an improved construction which obtains an air circulation within a larger area than has heretofore been possible in fans which oscillate about a single axis only.

With the above primary objects in view, it is another object of my invention to provide a construction of the above described character in which the number of operating parts is reduced to a minimum and which is compact in accordance with the demands and desires of manufacturers and purchasers alike and which is not only distinctive in its appearance and practical in its value but also reliable in its operation and efficient in its use.

It is a still further object to provide a device which is constructed of relatively simple parts

2

which are adapted to be readily assembled and which when once assembled are positively and securely retained in operative relationship and which cannot be readily separated from each other, either accidentally or otherwise.

Other prime objects of my invention include: first, the securement of a higher degree of accuracy and greater degree of variety in the manner of work performed therewith than has heretofore been possible with prior devices known in the art; second, the attainment of a higher speed of construction and assembly of the device due to its simplification of design and its unique composition of parts; third, the attainment of a flexibility or a capability of adjustment by which a variety of motions or movements can be obtained by means of the same device; fourth, the achievement of a greater ease in adjustment and repairs; fifth, the provision of an improved fan which may be made more economically and with fewer operations in the manufacture of its parts, as well as in the assembly of the same than prior devices known in the art; and sixth, the provision of such other improvements in and relating to fans of the type above referred to as are hereinafter described and claimed.

My invention also consists in certain new and original features of construction and combination of parts hereinafter set forth and claimed in conjunction with the annexed drawings which illustrate a certain form of embodiment thereof, which form is deemed preferable and is a specific disclosure for the purpose of illustrating one embodiment of the invention by way of an example since the same has been found in practice to give satisfactory and reliable results. It is to be understood that the various parts of which the invention consists, can be variously changed within the scope of the appended claims without departing from the broad aspects and spirit of the invention and that the same is not to be limited to the precise arrangement and organization of the instrumentalities as herein shown and described.

To the above cited and other ends and with the foregoing and various other novel features and advantages and other objects of my invention as will become more readily apparent as the description proceeds, my invention consists in certain novel features of construction and in the combination and arrangement of parts as will be hereinafter more particularly pointed out in the claims hereunto annexed and more fully de-

scribed and referred to in connection with the accompanying drawings wherein:

Fig. 1 is a small scale side elevational view of a fan embodying my invention;

Fig. 2 is a partial side elevational view of certain parts of a fan structure showing features of my invention, the cover members having been removed for purposes of clarity;

Fig. 3 is a rear elevational view of the structure shown in Fig. 2;

Fig. 4 is a sectional view along the line 4-4 of Fig. 2;

Fig. 5 is an enlarged view of the yoke and swivel members of the structure of my invention;

Fig. 6 is a top plan view of the gear box of the structure with the top plate removed therefrom;

Fig. 7 is a side elevational view of the clutch of the structure; and

Fig. 8 is a partial side elevational view of the bracket member of the structure.

In the following description and claims, various details will be identified by specific names for convenience. These names, however, are intended to be as generic in their application as the art will permit.

Referring now to the drawing in detail, in which similar characters of reference indicate corresponding parts in the several figures, and referring more particularly to the preferred form of my invention selected for illustrative purposes, I have shown a fan construction of the usual design comprising a base 10, a fan-wheel or propeller-wheel 12, a guard member 14, enclosing the fan-wheel, and a main body portion consisting of a housing 16 to which the guard member may be secured and which encloses the fan driving motor (not shown), all as is conventional and forms no part of the present invention.

The motor has a shaft 18 which extends forwardly therefrom through an opening in the forward end of the housing 16 and the fan-wheel 12 is mounted on the forward end thereof in the well known manner.

A gear box 20 is provided with a cover member 22 which may be secured thereto as by screws 24 or the like and legs 26 which extend forwardly therefrom are fixed to the housing 16 in any suitable manner.

The shaft 18 also extends rearwardly from the housing and into the gear box and is provided with a worm 30 which extends outwardly through and beyond the gear box, as is best shown in Fig. 6.

A worm gear 32 meshing with and driven by the worm 30 in the gear box is rotatable on a shaft 34 with which is also rotatable a second worm 36 adapted to drive a worm wheel 38 which is mounted adjacent the floor of the gear box.

A vertical staff member 40 extends through the worm wheel 38, is rotatable in the gear box, the gear 38 being rotatable thereon and has an upwardly extending free end which is threaded and adapted to receive a clutch 42. A clutch 42 has an internally threaded bore 44 in its lower end and is thereby adapted to be screwed up and down in the staff 40.

A clutch washer 46 (see Fig. 7) having serrations on its opposite face is disposed on the staff 40 and rests on the worm wheel 38. The lowermost surface of the clutch 42 is serrated as at 48, which serrations engage with the serrations on the upper face of the washer 46 when the clutch is screwed downwardly upon the staff 40. Thus the gear 38 is locked to the staff as member 42

is screwed downwardly so that the staff is rotated by worm 30, gear 32 and worm 36.

The clutch member 42 may be of such dimension as to extend upwardly through an opening in a casing 50 which encloses the open rear end of the housing 16, gear box, and other related parts herein being described and as is best shown in Fig. 1.

The upper end of the clutch may be knurled as at 52 to facilitate manual engagement for turning thereof.

A lug member 60 is secured to and extends downwardly from a box 62 which is a part of the housing 16. The lug 60 is secured between the opposite side arms 64 and 64 of a yoke 66 by means of a yoke pin 68 which extends through openings 70 in the arms.

The lower end 67 of the yoke 68 is oscillatable in a bore in a swivel 72. A pin member 74 between the yoke and swivel prevents separation of members 68 and 72.

The upper extremity of the base 10 is bifurcated so as to provide a pair of ears 76 and 76. The swivel 72 is disposed between these ears and a pivot 78 connects members 72 and 76 for adjustment of the former in vertical planes. A locking screw 80 is in threaded engagement with one ear 76 for bearing on the swivel to hold it in adjusted position.

The outer free end of the worm 30 meshes with a worm gear 90 which is rotatable on a stud 91 adjustable up and down in a slot 93 of a lug 94 carried by gear box 20.

An adjusting nut 96 is threadedly engageable with 91 which holds the worm gear 90 relative to the lug. Adjustment of the worm gear up and down may thereby be obtained by moving member 91 longitudinally of the slot 94 whereby engagement and disengagement of the worm gear 90 from the worm 30 may be obtained as desired.

The adjusting nut 96 may have an extension of such dimension as to extend the same outwardly through a suitable opening in the casing 50, whereby manual adjustments of the worm gear 90 relative to the worm 30 may be made as desired. A tool may be inserted in said opening for engaging and turning said nut 91.

An arm 100 has one end fixed to the yoke 64 as by a screw 102 or the like. At the opposite extremity of the arm, one end of a pitman or link 104 is pivoted by means of a pin 106. The opposite and upper extremity of the pitman 104 is eccentrically secured to a side face of the worm gear 90 at 105 so that as the worm gear is rotated, the housing and fan are caused to oscillate up and down in vertical planes. That is to say, the main body portion of the fan structure is oscillated up and down in vertical planes.

A stationary bracket 110 has one end thereof fixed to the swivel 72 as by a screw 112 or the like and has fixed to its opposite free end the lower portion 114 of an upwardly extending clevis.

The upper portion 116 of the clevis is pivotable relative to the lower portion 114 thereof and its upper extremity is bifurcated so as to hold in pivotal relation one end of a connector 118 by means of a pivot pin 120.

A lever 122 is fixedly connected at one end to the lower extremity of the staff 40 which extends downwardly below the gear box. The other end of member 122 is pivotally connected at 124 to the outer end of connector 118.

As the staff 40 is rotated, the lever 122 con-

nected thereto is caused to sweep around in a rotary motion.

The lower portion 114 of the clevis being fixed to the stationary bracket 110, its position is fixed and it serves as the point from which the horizontal, oscillatory movement of the housing is accomplished through the linkage which includes the upper portion 116 of the clevis, the connector 118, and the lever 122. That is to say, as the lever 122 sweeps around, the vertical axis of the staff 40 is rotated in a circulatory movement in a horizontal plane about its axis.

Thus it will be observed that when the fan is in operation, the fan housing is given oscillatory movements in a horizontal plane.

A supplementary casing 130 may be provided and fixed to the casing 50 as by screws 132 or the like. This member is of such configuration and design as to enclose the working parts rearward of and beneath the housing and casing. If desired, the casing 50 and supplementary casing 130 may be made integral with each other.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modifications and variations as fall within the meaning and purview and range of equivalency of the appended claims are therefore intended to be embraced therein.

What it is desired to claim and secure by Letters Patent of the United States is:

1. In a fan structure comprising in combination, a support, a housing connected to said support and oscillatable relative thereto, a motor carried in said housing, a shaft driven by said motor, a worm on said shaft, a fan wheel driven by said shaft, a staff, means driven by said shaft for rotating said staff, a clutch adjustable on said staff for engaging said staff with said means between operating and non-operating positions, a drive means comprising a worm gear meshing

35

40

45

with said worm on said shaft and adjustable into and out of engagement therebetween, a pitman eccentrically secured to the worm gear, an arm connecting said housing and said pitman whereby with the worm gear in engaged position relative to the worm on said shaft, said housing and shaft and fan wheel are oscillated in vertical planes, a stationary bracket having one end fixed to said support, a linkage connected between said stationary bracket and said staff whereby said housing moves in a horizontal oscillatory movement upon the rotation of said staff.

2. In a fan structure comprising in combination, a support, a housing connected to said support and oscillatable relative thereto, a motor carried in said housing, a shaft driven by said motor, a fan wheel driven by said shaft, a staff in said housing, means driven by said shaft for rotating said staff, a clutch adjustable on said staff for moving said staff into and out of operating position with said means, a worm on said shaft, a rotatable worm gear meshing with said worm and being adjustable into and out of engagement therebetween, a pitman eccentrically secured to said worm gear, a pivotable arm connecting said housing and said pitman whereby with said worm gear in engaged position relative to said worm, said housing and shaft and fan wheel are oscillated in vertical planes, a stationary bracket having one end fixed to said support, a linkage connected between said stationary bracket and said staff whereby said housing moves in a horizontal oscillatory movement upon the rotation of said staff.

GEORGE E. MARTIN.
